UNITED STATES PATENT OFFICE.

JAMES CLARENCE BURNE, OF WESTFORD, MASSACHUSETTS, ASSIGNOR TO MONROE CALCULATING MACHINE COMPANY, OF NEW YORK, N. Y., A CORPORATION OF NEW YORK.

ATTACHMENT TO ADDING-MACHINES.

1,358,517.

Specification of Letters Patent. Patented Nov. 9, 1920.

Application filed March 15, 1919. Serial No. 282,813.

To all whom it may concern:

Be it known that I, JAMES CLARENCE BURNE, a citizen of the United States, residing at Westford, in the county of Middlesex and State of Massachusetts, have invented certain new and useful Improvements in Attachments to Adding-Machines, of which the following is a specification.

This invention relates to calculating machines of the type having a base on which are disposed various keys, and a carriage which is movable transversely thereon and is so connected thereto that part of it can be raised therefrom for various purposes, especially for returning the result dials carried thereby to the zero point.

A similar type of machine is shown in patents to F. S. Baldwin on calculating machine, December 2, 1913, No. 1,080,245, and F. S. Baldwin, on zero setting mechanism, August 6, 1918, No. 1,275,119.

The carriage of such machines is usually slidable transversely with a suitable pivot rod carried in suitable bearings at the back 25 of the base, and also carries a clearout crank.

On this type of machines, there are usually two result dials, one of which is cleared by turning the clearout crank away from the operator, and the other is cleared by lifting 30 the carriage and turning the clearout crank toward the operator.

As now constructed, such machines are provided with a main crank which, with the clearout crank, is operated by the right hand, but not at the same time. It also has a carriage shifting lever operated by the left hand to shift the carriage and also to lift such part of it as can be raised from the base in order to permit the clearout crank 40 to be turned toward the operator for the purpose of returning one of the result dials to zero.

The carriage shifting lever must be held by the left hand or balanced carefully while 45 the clearout crank is being turned toward the operator to return one dial to zero. This necessitates such left hand being removed from its position on the account which is being tabulated, and the place is 50 lost.

The carriage may be raised and held by the left hand while the clearout crank is

turned by the right hand, but this is less convenient.

The purpose of my device is to provide an attachment operative by the clearout crank alone, without the assistance of the carriage shifting lever or of the left hand in any way. Its operation in turning from the operator is not affected, but in turning 55 toward the operator, it will lift part of the carriage from the body, thus disengaging gears and will hold this part of the carriage in the raised position until the zero is obtained. 60

Such lifting means must be operative from any position in the traverse of the carriage.

In the drawing, Figure 1 is a perspective view of a calculating machine with my attachment. Fig. 2 is an elevation of the carriage and adjoining parts from the side of the clearout crank, the carriage being shown in the down position. Fig. 3 is an elevation similar to Fig. 2 showing the carriage raised. Fig. 4 is a detail view from the front of the machine showing my preferred form of returning spring. Fig. 5 is a plan view of my attachment shown as provided with two lifting arms. Fig. 6 is a detail view in perspective showing a modification of my device. 70 75 80

Fig. 7 is a plan view of the carriage in the type of machine to which my device can be attached, the cover being broken away for clearness and some parts of my device being also broken away. Fig. 8 is a sectional elevation on line 8—8 of Fig. 7 looking from the right. Fig. 9 is a sectional elevation on line 9—9 of Fig. 7 looking from the left. 85

In the drawings, B represents the base or casing of a calculating machine shown as being rectangular, having a back 5, front 8, sides 6 and 7, and top 9, and on the top are disposed keys A. 90

At the back is located a pivoted carriage C which is shown as considerably wider than the base and as being carried by and fixed to a rod 10 which is pivotal in and slides in suitable bearings 1 attached to the back top of the base whereby the carriage is endwise 95 shiftable and pivoted. 100

In the particular type of machine shown, especially in Figs. 7, 8 and 9, the carriage C has a principal series of registering or result

dials 20, each provided with a gear wheel, such as 151, in mesh each with one of a series of gear wheels 150 in the casing B of the machine and a secondary or upper result 5 series of registering dials 21.

The principal series is carried by shaft 60 and the secondary series by shaft 84, both of which extend through a partition M.

On the other side of this partition M is a 10 shaft 40 which carries a clearout crank G of well known construction and O is the main crank at the right of the machine. This shaft 40 is connected with means, shown as including the gears 110 and 111 carried thereby, which engage gears 114 and 112 carried respectively by the shafts 60 and 84, which carry the principal series of registering dials with their gears, and the secondary series of registering dials respectively, as shown in patent to Baldwin, No. 1,275,119, August 6, 1918, whereby, when the shaft 40 is rotated in one direction it will set the principal series of dials to zero, and when it is rotated in the opposite 25 direction, it will set the opposite series of dials at zero. It is considered unnecessary to further describe such zero-setting means, as a type of such means is explained in detail in said Baldwin patent.

30 With such means, it is necessary, in order to disengage the gear wheels of the principal series of registering dials from the gears in the casing, to raise the carriage in order to set back such principal series to zero by the 35 last-named means. This has been generally accomplished by a carriage shifting lever F operated by the left hand.

40 F is the carriage shifting lever, at the left front of the machine, which is connected in a well known manner with devices whereby the part of the carriage C nearest the operator will be lifted when F is turned and also moved to the left or right. To keep this part of the carriage lifted, F must 45 be turned to the dotted line position shown in Fig. 1, and either held there or balanced in that position.

The above parts are all old.

50 My device comprises a cam H fixed to the shaft 40 of clearout crank G of the form shown. Cam H is shown as a perfect disk with a section 41 cut out.

I provide lifting means K, which is shown as revolvable in hangers 30 and 31 which 55 project from the carriage C a sufficient distance to permit lifting arm 33, which is bent from or attached to the long bearing member 29 of K, to clear the carriage, but to engage the top of base B or, preferably, the 60 top of the spacing part thereof 22 when K is revolved in its hangers. Lifting member K is also shown as having a power arm 32, which is of such length that it extends to cam H and into cut-away part 41, as shown 65 in Figs. 1 and 2. In Fig. 2, I show a stop

pin 12 to limit the downward motion of arm 32.

When clearout handle G is turned away from the operator in the direction opposite to the arrow in Fig. 2, the lifting arm 33 70 is disengaged from the base, as the power arm 32 is raised and rests idly on the curved surface 42 of cam H. When G is turned toward the operator in the direction of the arrow, however, the power arm 32 is depressed, as shown in Fig. 3, depressing arm 33 which engages the top 9 of base B, and the part of the carriage toward the operator is lifted to such a point that the gears are disengaged by the continued motion of G 80 and cam H. The cam is so cut that, after being lifted, that part of the carriage is kept in the raised position during a great part of the rotation of crank G.

As shown in Fig. 5, instead of using one 85 lifting arm 33, I may use two, as 33 and 34, whereby if one does not strike true on the top of the corrugations in the part 22, the other one will, and more even action is obtained.

90 Instead of the stop pin 12, I prefer to use a double action returning spring shown at 13 as of the hairpin type, with the two arms which extend one above and the other below power arm 32 and as fixed to the hanger 95 30 whereby whichever way 32 is moved, it will be brought back to its normal position when free.

95 In Fig. 6, I show a somewhat modified device wherein the clearout crank shaft 40 100 carries a gear 50, which engages another gear of the same size 51 carried idly by stud 52 and fixed to cam H. Cam H projects toward the operator from the front of carriage C in position to engage the tail 61 105 of a lifting member L, pivoted at 63 to the carriage and having its other end 62 bent down at 64 as shown.

A turn of G toward the operator will 110 turn H in the opposite direction and, when tail 61 falls into cut-away part 51, its lifting end 64 is depressed until it engages base B, when the action continues and part of the carriage is lifted as in the first construction.

115 So far as the operation of my attachment is concerned, the spacing part or rail 22 may be regarded as part of the base. The bearing member, such as 29, and the part of lifting member L between the end of tail 61 and the part 64 may be regarded as transmission members extending from proximate the clearout crank to the base in whatever position the carriage may be. The whole of members K, L, or their equivalents, 120 125 may be regarded and described as lifting means.

I claim:

1. In a calculating machine, having a base, a carriage movable transversely there- 130

- on and so connected thereto that part of it can be raised therefrom, a clearout crank carried by the carriage, and result dials carried by the carriage and operative by the 5 clearout crank when said part of the carriage is raised from the base, the combination of a cam formed as a disk with part cut away revoluble by the clearout crank, with lifting means comprising a long bearing member pivoted to the carriage transversely of the base having at one end a power arm so bent as to engage with and be operative by the cam, and at the other end one or more lifting arms, the arms of 10 such lifting means being of such size and location that the lifting arm or arms engage the base and lift the carriage during a predetermined period while the clearout crank is being turned in one direction but are 15 disengaged from the base and are idle when the clearout crank is turned in the other direction, together with a returning spring between the carriage and lifting member so arranged as to return the lifting means to its 20 normal position.
2. In a calculating machine, having a base, a carriage movable transversely thereon and so connected thereto that part of it can be raised therefrom, a clearout crank 25 carried by the carriage, and result dials carried by the carriage and operative by the clearout crank when said part of the carriage is raised from the base, the combination of a cam revoluble by the clearout 30 crank, with lifting means comprising a long bearing member pivoted to the carriage transversely of the base having at one end a power arm operative by the cam, and at the other end a lifting arm, the arms of 35 such lifting means being of such size and location that the lifting arm engages the base and lifts the carriage during a predetermined period while the clearout crank is being turned in one direction but is disengaged from the base and is idle when the clearout crank is turned in the other direction.
3. In a calculating machine, having a base, a carriage movable transversely thereon and so connected thereto that part of it 40 can be raised therefrom, a clearout crank carried by the carriage, and result dials carried by the carriage and operative by the clearout crank when said part of the carriage is raised from the base, the combination of a cam revoluble by the clearout 45 crank, with lifting means comprising a long bearing member pivoted to the carriage transversely of the base having at one end a power arm operative by the cam, and at the other end a lifting arm, the arms of such lifting means being of such size and location that the lifting arm engages the base and lifts the carriage during a predetermined period while the clearout crank is being turned in one direction but is disengaged from the base and is idle when the clearout crank is turned in the other direction.
4. In a calculating machine, having a base, a carriage movable transversely thereon and so connected thereto that part of it can be raised therefrom, a clearout crank carried by the carriage and result dials carried by the carriage and operative by the clearout crank when said part of the carriage is raised from the base, the combination of a cam revoluble by the clearout 50 crank, with lifting means comprising a long bearing member pivoted to the carriage transversely of the base having at one end a power arm operative by the cam, and at the other end a lifting arm, the arms of such lifting means being of such size and location that the lifting arm engages the base and lifts the carriage during a predetermined period while the clearout crank is being turned in one direction but is idle when the clearout crank is turned in the other direction.
5. In a calculating machine having a base and a carriage movable transversely thereon and so connected thereto that part of it can be raised therefrom, a clearout crank carried at one end by the carriage, and result dials carried by the carriage and operative by the clearout crank when said part of the carriage is raised from the base, the combination of a cam in the form of a disk having a cut-away part and revoluble by the clearout crank, with lifting means including a transmission member extending from proximate the clearout crank to the base in whatever position the carriage may be, and a power member operative by the cam together with a lifting member in operative relation with the base.

In testimony whereof I have affixed my signature.

J. CLARENCE BURNE.
